UNITED STATES PATENT OFFICE.

PAUL J. REES, OF YORK, PENNSYLVANIA, ASSIGNOR OF ONE-HALF TO EUGENE U. GIBBS, OF YORK, PENNSYLVANIA.

GUIDE VANE.

Application filed April 21, 1924. Serial No. 708,065.

To all whom it may concern:

Be it known that I, PAUL J. REES, a citizen of the United States of America, residing at York, in the county of York and

5 State of Pennsylvania, have invented certain new and useful Improvements in Guide Vanes, of which the following is a specification.

My invention relates to improvements in 10 the construction of turbine wicket gate mechanisms and especially to improvements in guide vanes.

Heretofore it has been customary to form 15 these guide vanes or wicket gates of cast metal which has many disadvantages. Attempts have been made to form these vanes of sheet or wrought metal but in order to make the vanes of sufficient strength and rigidity, the construction was so complicat- 20 ed as to increase the cost and labor of manufacture.

An important object of my invention is to 25 provide a device of this character which will be formed of sheet or wrought metal and which will be of strong construction and yet will be cheap and convenient to manufacture.

Another object of my invention is to provide a method of constructing guide vanes 30 of this character which will be simple and inexpensive but which will produce a vane of strong and durable formation.

Other objects and advantages of the invention will be apparent during the course 35 of the following description.

In the accompanying drawings which form a part of this specification and wherein like characters of reference designate like parts throughout the same:

40 Figure 1 is a perspective view of my improved guide vane,

Figure 2 is a transverse section on the line 2-2 of Figure 1,

Figure 3 is a perspective view of the guide 45 vane during its construction,

Figure 4 is an end elevation of the same,

Figure 5 is a perspective view of a modification,

Figure 6 is a side elevation thereof, and

50 Figure 7 is an end view of the same.

In the drawings, wherein for the purpose

of illustration is shown a preferred embodiment of my invention, the numeral 5 designates the stem of the vane which is preferably formed of round bar stock. The two 55 plate sections 6 and 7 have their ends bevelled at 8, and the upper section 6 is bent upon itself into a substantially V-shaped formation. The lower section 7 is bent upon itself into a substantially V-shaped 60 formation and the stem 5 is adapted to be arranged between the two sections. The inner portions of the bevelled ends of the two sections 6 and 7 are adapted to contact with the stem 5. The space between the inside 65 portions of the bevelled edges is slightly less than the diameter of the stem, but a straight line A—A connecting the outside edges of the plate sections will be approximately tangent to the stem, as seen in Figure 4. 70

The straight line A—A forms, with the bevelled edge of the plate section and the portion CE of the stem, an approximate triangle, there being four of such triangles. These spaces or triangles are filled in by 75 autogenous welding, or fusion of metal as shown at 9. These four spaces or triangles run longitudinally along the stem and when filled by fusion of metal, the guide vane becomes a complete unit without seams, rivets 80 or screws. Although the drawing shows the welding as separate from the plate sections and stem, this is only for purposes of illustration, and the entire structure, in reality, becomes a single unit. 85

The portion CE of the stem forms with the bevelled edge 8 of the plate a suitable V for welding without any additional labor cost and the welding is on straight longitudinal lines and can be done with the automatic type of electric welder, which is rapid and efficient. The welding has sufficient contact with the edges of the plates and with the stem surface to insure ample strength. 90

The plate sections are easily formed and as the stem is made from a sawed off length of bar stock, it requires no forging or machining to adapt it to its location between the two plate sections. It will readily be appreciated that this is a decided advantage 95 from the point of cost over a stem which 100

is made to conform to the side surfaces of the plate sections by forging or machining before it can be secured thereto.

The modification shown in Figures 5, 6, and 7, is for use where it is desired to have the wicket gate turn upon a stationary stem instead of upon its own integral stem as in the embodiment shown in Figures 1 to 4. The numeral 10 designates the two bearings 10 formed from short lengths of round bar stock with holes 11 drilled through their centers for the reception of the stationary stem 14 and these bearings are arranged at each end of the plate sections. These bearings 15 are secured to the plate sections in the same manner as the stem in the preferred embodiment of my invention, but the bevelled edges 12 of the plate sections only extend the length of the bearings. The two 20 plate sections have their edges between the bearings, meet, and these meeting edges are also bevelled at 13 and this seam is welded on both sides.

The lower end of the vane is offset at 25 and a steel block 16 is secured to this end by welding in openings 17 in the plate sections. This block is provided with an opening 18 to which the actuating link 19 is secured by means of the pin 20.

While I have shown and described the preferred embodiment of my invention, it is to be understood that various changes in shape, size and arrangement of parts may be resorted to without departing from the 30 spirit of my invention or the scope of the subjoined claims.

Having described my invention what I claim and desire to protect by Letters Patent is:

1. A guide vane comprising two plate 40 sections bent to form substantially V-shapes, a stem arranged between the plate sections and welded to the ends thereof.

2. A guide vane comprising a plate section 45 having bevelled edges, said plate section being bent into substantially V-shape, a stem adapted to contact with the bevelled edges of the plate section and welded thereto.

3. A guide vane comprising two plate sections 50 having bevelled edges, said plate sections being bent into substantially V-shapes, a stem arranged between the plate sections and contacting with the bevelled edges of the sections, the angles formed by the 55 bevelled edges and the surface of the stem being filled with autogenous welding.

4. A guide vane comprising two sheet metal sections, and a stem arranged therebetween and welded to the ends thereof. 60

5. A guide vane comprising two plate sections having their edges bevelled, said plate sections being bent into substantially 65 V-shapes, a stem arranged between the plate sections and contacting with the bevelled edges thereof, whereby a line drawn through the outer points of the plate sections will be approximately tangent to the stem, the longitudinally extending angles formed by the bevelled edges of the plate 70 sections and the surface of the stem being filled with autogenous welding.

6. A guide vane comprising two plate sections bent to form substantially V-shapes, and a stem arranged between the ends of the 75 plate sections and secured thereto.

In testimony whereof I affix my signature.

PAUL J. REES.
